PAPER-ROLL-WINDING MECHANISM

Application filed April 19, 1929. Serial No. 356,388.

This invention relates to improvements in winding mechanism for winding a continuous web of paper or a like material into a roll.

In winding machines for winding web material into rolls as ordinarily operated, the 5 end of the web is threaded through the winder mechanism and manually given a single turn or wrap around a core or shaft on which the web of material is to be wound, this core resting on the surfaces of a pair of winding drums 10 which rotate the core and web roll by frictional engagement therewith.

In this class of winders, it is important that the roll be evenly wound from the start of the 15 winding operation. The winder cores or shafts, however, have to be made as light as possible for convenience in handling, so that the pressure of the winding shaft against the winding drums is comparatively slight at 20 the start of the winding operation; this pressure not being sufficient to hold the web roll in frictional engagement with the winding drums with sufficient pressure to provide an even winding of the web material. These 25 light winding shafts or cores are furthermore, under modern practice, of considerable length and this tendency of the web to wind unevenly cannot be satisfactorily overcome by pressures applied at the ends of the shaft, as has 30 been proposed, because, owing to the spring of the shaft, the pressure at the center would not be the same as at the ends. Another proposal has been to add a presser roll or 35 ironing roll on top of the roll of web material as it is wound. This will effect, to some extent, even winding, but is objectionable because of the amount of mechanism required for supporting it, and for other reasons.

It is the object of the present invention to 40 produce an improved winding mechanism by the use of which a roll may be evenly wound from the start of the winding operation and so that the objectionable ironing or presser roll, or pressure applied to the ends of the web 45 roll shaft is unnecessary; the desired result being attained by an adjustment of the winding drums themselves so that the roll of web material may be acted on by the winding drums with the desired amount of friction 50 necessary to insure even winding.

It is a further object of the invention to produce a mechanism of simple form whereby the winding drums may be easily and quickly adjusted toward and from each other to act on the winding roll with the desired amount 55 of friction for even winding.

With these and other objects not specifically referred to, the invention consists in certain novel parts, arrangements and combinations which will be described in connection with the accompanying drawings and 60 pointed out in the claims hereto annexed.

In the drawings,

Figure 1 is a plan view of a mechanism of simple form embodying the invention. 65

Fig. 2 is an end view of the machine shown in Fig. 1;

Fig. 3 is an end view, partly in section, on an enlarged scale, showing one position of the winding drums with relation to the 70 winding roll, and

Fig. 4 is a view similar to Fig. 3, showing the parts in the position to which the winding drums may be adjusted to obtain the desired 75 frictional contact with the winding roll.

Referring to said drawings, the invention generally consists in the provision of means for evenly adjusting the winding drums to and from each other, so that the winding roll may be dropped into engagement with the 80 winding drums to an extent sufficient to produce the required pressure to effect even winding.

In the particular machine selected to illustrate the invention, the parts of the machine 85 are supported in frames 1, 2, and the winding mechanism includes a pair of winding drums 3, 4 supported at each end on shafts 5, 6 mounted in bearings 7, 8 in bearing blocks 7', 8' which have a bolt and slot connection in the frames 1, 2; the purpose of this bolt and slot connection being hereinafter referred to.

Each of these drums is a driven drum, being driven in any suitable manner, as from electric motors 9, 10, suitably supported on beds 11 which have bolt and slot connections 12 in a base plate 13. The winding roll is indicated by the numeral 14, the web material which forms the roll being wound 95 on a shaft or core 15. It will be observed 100

that the driving mechanism for each roll is in axial alignment therewith and partakes of the lateral adjusting movement of the roll. With this construction, therefore, the roll shafts and the driving mechanism therefor are kept in proper alignment and there is no liability of distortion of the shafts or the rolls, so that a true winding surface is always presented to the roll of material which is being wound.

Referring to Fig. 3, it will be observed that if the winding drums are close together, as in the ordinary practice, the weight of the winder shaft will give a force which may be called A, and this force will exert a pressure between the winding drums 3, 4 and the winding web roll 14 which will equal that diagrammatically illustrated as at B—B. If now, the winding drums 3, 4 be moved apart an equal distance from each other the same force A will give a greater pressure, diagrammatically illustrated by C—C, and the frictional engagement of the winding drums and winding roll will be sufficiently increased to effect an even winding of the roll at the start of the widing operation. It will thus be seen that the desired increase in pressure is obtained without the necessity of adding a presser roll above the winding roll, or mechanism of increasing the pressure at the ends of the roll and an even winding of the web into the roll from the start of the operation is obtained in very simple manner.

Any desired means may be provided for adjusting the winding drums and their driving mechanism. In the particular construction illustrated, at each end of the drums is provided a bracket 16 in which is supported a double ended screw 17, one end of this screw having a right hand thread and the other end a left hand thread, the ends of the screw screwing into extensions 18, 19 of the drum bearings 7, 8. Similarly, the driving motors may be adjusted laterally by means of screws 20, 21 threaded into thrust blocks 22, on the motor beds 11 before referred to. The bolt and slot construction in the motor beds and the bolt and slot connection 25 for bearings permit this adjustment to be made, and the screws 17 may be readily manipulated by means of an operating collar 23 provided with apertures 24 in which may be inserted a suitable tool for rotating the collar. While this means of adjustment is a convenient one, it will be understood that the invention is not to be restricted to this, but other suitable adjusting devices may be used, as desired.

It will be understood that the invention is not to be restricted to the exact form and construction of the parts shown, but that variations in these may be made without departing from the invention as defined in the appended claims.

What is claimed is:

1. In a winding mechanism for winding a web of material into a roll, the combination of a pair of winding drums, means in axial alignment therewith for driving them, a winding roll in frictional engagement with the drums, means for effecting an even lateral movement of each of the drums to and from each other to permit the roll to engage the winding drums with varying pressures, and means for effecting a similar lateral movement of the driving means.

2. A winding mechanism for winding a web of material into a roll, the combination with a pair of winding drums, means in axial alignment therewith for driving the drums, a winding roll frictionally engaging the drums, bearings in which the drums are mounted, a right and left hand threaded screw connected with the bearings, and means for effecting a movement of the screw to laterally adjust each of the drums with respect to each other.

3. A winding mechanism for winding a web of material into a roll, the combination with a pair of winding drums, means in axial alignment therewith for driving the drums, a winding roll, frictionally engaging the drums, a frame, bearings in which the drums are mounted, bolt and slot connections between the bearings and the frame, a right and left hand threaded screw connected with the bearings, means for turning the screw to effect an even lateral adjustment of the bearings to and from each other, and bolt and slot connections for the driving means so that the driving means will partake of the lateral movement of the drums.

4. A winding mechanism for winding a web of material into a roll, the combination with a pair of winding drums, means in axial alignment therewith for driving the drums, a winding roll frictionally engaging the drums, bearings in which the drums are mounted, a right and left hand threaded screw connected with the bearings, and means for turning the screw to effect an even lateral adjustment of the bearings to and from each other and a simultaneous and similar movement of the driving means.

In witness whereof, we have hereunto set our hands.

CHARLES W. VALENTINE.
ALFRED F. HELIN.
